UNITED STATES PATENT OFFICE.

JOHN E. ANNIS, OF CHATTANOOGA, TENNESSEE.

DESIGN FOR A METAL SHINGLE.

43,400.

Specification for Design.

Patented Dec. 31, 1912.

Application filed August 20, 1912. Serial No. 716,105. Term of patent 14 years.

To all whom it may concern:

Be it known that I, JOHN E. ANNIS, a citizen of the United States, residing at Chattanooga, in the county of Hamilton and State of Tennessee, have invented a new, original, and ornamental Design for Metal Shingles, of which the following is a specification, reference being had to the accompanying drawing, forming part thereof.

The figure is a plan view of the metal shingle, showing my new design.

I claim:

The ornamental design for a metal shingle, as shown.

JOHN E. ANNIS.

Witnesses:

CLARA M. KILROY,
GILBERT J. WHITE.
